(57) **CLAIM**

The ornamental design for a tent, as shown and described.

DESCRIPTION

FIG. 1 is a front perspective view of a tent showing our new design;

FIG. 2 is a rear perspective view thereof;

FIG. 3 is a front elevational view thereof;

FIG. 4 is a rear elevational view thereof;

FIG. 5 is a side elevational view thereof;

FIG. 6 is a side elevational view thereof;

FIG. 7 is a top plan view thereof; and,

FIG. 8 is a bottom plan view thereof.

The first variant of the design is shown in FIGS. 1-8. The second variant of the design is shown in FIGS. 9-10. Applicants reserve the right to amend this application and/or to file one or more divisional or continuation applications to specifically claim or disclaim any of the elements in the drawings.
